UNITED STATES PATENT OFFICE.

JAMES L. MCCLINTOCK, OF CLEARWATER, KANSAS.

POST-FOUNDATION.

No. 925,940.

Specification of Letters Patent.

Patented June 22, 1909.

Application filed March 3, 1909. Serial No. 481,126.

To all whom it may concern:

Be it known that I, JAMES L. MCCLINTOCK, a citizen of the United States, residing at Clearwater, in the county of Sedgwick 5 and State of Kansas, have invented new and useful Improvements in Post-Foundations, of which the following is a specification.

This invention relates to post foundations and more particularly to a foundation formed 10 of concrete or cement.

The object of this invention is to provide a foundation for a post which will be absolutely rigid and at all times retain the post in its original position under all conditions. 15 This foundation will act in the same manner with a built up concrete post or with a wooden post embedded therein.

The advantages of this foundation are obvious and apply to all posts subject to an 20 unequal strain, such as a gate post, a corner post for a fence, a telegraph pole or a flag pole.

The preferred form is illustrated in the accompanying drawings, yet it is to be understood that minor detail changes may be made without departing from the scope of 25 the invention.

Figure 1 is a view in vertical section through one form of my improved foundation. Fig. 2 is a plan view of the same. 30 Fig. 3 is a plan view of a modification. Fig. 4 is a view in elevation of a modification showing the foundation in vertical section. Fig. 5 is a sectional view taken on the line 35 V, V of Fig. 4.

In Fig. 1, which illustrates a form of my invention as applied to a gate post, 1 represents the upper face of the surrounding soil, 2 the loose surface soil and 3 the solid 40 subsoil. 4 is a substantially circular base extending to a considerable depth in the subsoil. 5 is a gate post embedded in said base. In this instance the gate post is used in connection with a wire fence and as it is necessary in making fences of this description to place the longitudinal strands under great tension, the gate post 5 will be subjected to a considerable strain in the direction 45 of the arrow a. 6 is a spur projecting from the upper portion of the base 4 to about the depth of the surface soil 2 and in the direction of the previously determined strain upon the post 5. 7 is a projection 50 on the underside of the spur 6 near the outer end thereof extending into the subsoil 3. The base 4, spur 6 and extension 7 are all

formed of concrete or cement. 8 is a stake extending through the projection 7 to a considerable distance into the subsoil 3, preferably below the base 4, and its head is 60 embedded in the spur 6. 9 is a reinforcing member embedded in the spur, lying with one end adjacent to the post 5 and with the other end adjacent to the stake 8.

The construction of such a foundation is 65 very simple and may be readily accomplished by any person of ordinary intelligence with very little difficulty, and by an extremely small expenditure of labor or money, as compared with the old methods 70 of timber bracing.

The excavation for the base 4 is first made substantially circular in section and slightly larger than the post to be secured therein, a shallow extension in the direction of the 75 strain upon the post is then made to provide for the spur 6. This last named excavation is generally made down to the subsoil though in many cases this is not desirable, and for that reason the projection 7 is formed on the spur 6. The excavation for the projection 7 may be made by an ordinary post hole auger and is carried down to at least a short distance beneath the subsoil. The stake 8 is then driven through the center of the excavation last named until the head thereof is 80 about half way below the surface of the soil 1 in the shallow excavation extending from the circular excavation. The cement or concrete having been properly mixed, the bottom of the circular excavation is covered and the post 5 held in position while more concrete is tamped in around the post filling the space therearound. The shallow excavation for the extension is then filled with soft 85 cement or concrete approximately to the height of the head of the stake, and the reinforced member 9 is placed thereon and the remainder of the excavation filled. The top of the foundation thus constructed is leveled 90 off to correspond with the surface of the surrounding soil leaving a collar surrounding the post to shed water if desired, and the concrete allowed to set.

The ordinary manner of setting a fence post is to make an excavation of sufficient size, insert the post and then tamp earth around the same. As soon as a post secured in this manner is subjected to an excessive strain in one direction, the top of the post is bound to give in the direction of the strain, for the reason that the bottom is securely 105 110

held by the solid subsoil and the lighter surface soil will be pushed aside by the exertion of the strain. In my foundation the spur 6 extends in the direction of the strain and through the surface soil, and at the same time securely holds the head of the stake 8, which is driven to a considerable depth into the solid subsoil, and the spur 6 and stake 8 will coöperate in such a manner as to absolutely prevent any springing or movement of the base member 4 in the direction of the spur.

In wire fences the corner post is subjected to even greater strain than the gate post, and in applying a foundation of my construction to a corner post two spurs are provided which extend in the direction corresponding to the two lines of the fence, otherwise the construction is the same as illustrated in Fig. 1.

Telegraph poles and flag poles are extremely difficult to secure in an upright position without the use of additional braces or supports, and in most cases these braces or supports will spring loose under a terrific strain to which they are subjected. The strain on telegraph poles is the greatest where the line makes a curve or takes a corner. In Fig. 4 I have illustrated my foundation as applied to a telegraph pole or flag pole. In this case I provide a plurality of diametrically opposed spurs constructed in the manner illustrated in Fig. 1.

In some cases it is desirable to provide an additional brace for the post. In Fig. 4 I have illustrated a brace 11 secured to the post 10 at its upper end with its lower end 12 embedded in the spur 6 in proximity to the end of the reinforcing member 9 and the head of the post 8. The cement binds these three portions tightly together and prevents the springing or removal of the braces 11.

The stake 8 may be of wood or metal as desired without fear of deterioration for the reason that the part of the stake which comes in contact with the earth is a considerable depth below the subsoil and experience has taught us that both wood and metal will be preserved thoroughly in the subsoil away from air. The reinforcing member 9 may be either wood or metal and may be either scrap or constructed in any desired form, as it is embedded in the concrete it will not deteriorate.

In Fig. 5 I have illustrated a section taken through a foundation for a pole 10, and in such instances it may be desirable to extend the reinforcing member from one spur around the pole and into the other spur. Such a reinforcing member is indicated by 9^a. Again it may be desirable to provide a wire rope stay or guy, such as 13 from the top of the pole to the base. In such a case I have provided the reinforcing member with a double eye bolt 14, one eye of which projects

above the upper surface of the spur 6 to provide a means for securing stay 13, the other eye connecting, when practicable, with the reinforcing member embedded in spur 6.

Having described my invention I claim:—

1. A post foundation comprising a base of concrete, a spur of concrete projecting from the upper portion of the base, and a stake having its head embedded in said spur and extending downward into the soil.

2. A post foundation comprising a base of concrete, a post embedded therein, a spur of concrete projecting from the upper portion of the base, a stake extending downward into the soil from said spur and having its head embedded therein.

3. A post foundation comprising a base of concrete, a post embedded therein, a spur of concrete projecting from the upper portion of the base, a stake extending downward into the soil from said spur, and having its head embedded therein, and a post brace having one end embedded in said spur.

4. A post foundation comprising a base of concrete, a post embedded therein, a spur of concrete projecting from the upper portion of the base, a stake extending downward into the soil from said spur and having its head embedded therein, and a horizontal reinforcing member in said spur.

5. A post foundation comprising a base of concrete, a post embedded therein, a spur of concrete projecting from the upper portion of the base, a stake extending downward into the soil from said spur and having its head embedded therein, a horizontal reinforcing member embedded in said spur adjacent to the head of the stake and a post brace having one end embedded in said spur adjacent to the stake and reinforcing member.

6. A post foundation comprising a base of concrete, a post embedded therein, a spur of concrete projecting from the upper portion of the base, a stake extending downward into the soil from said spur and having its head embedded therein, a horizontal reinforcing member embedded in said spur adjacent to the head of the stake and means carried by the reinforcing member projecting above the foundation to form a securing means for a post brace.

7. A post foundation comprising a base of concrete, a spur of concrete projecting from the upper portion of the base, a projection of concrete on the underside of said spur, and a stake having its head embedded in said spur and extending through said projection into the soil.

8. A post foundation comprising a base of concrete, a plurality of spurs of concrete projecting from the upper portion of the base, and a plurality of stakes, each having its head embedded in a spur and extending downward into the soil.

9. A post foundation comprising a base of

- concrete, a post embedded therein, a plurality of spurs of concrete projecting from the upper portion of the base, a stake extending downward into the soil from each spur, and 5 having its head embedded therein, a horizontal reinforcing member embedded in each spur, one end lying adjacent to the post and the other end adjacent to its respective stake.
10. 10. The process of forming a concrete post foundation comprising the excavating of a substantially circular base, the excavating of a radial extension, the driving of a stake near the end of said extension and the filling of the 15 excavations with soft concrete embedding the end of the stake therein.
11. The process of forming a concrete post foundation comprising the excavating of a substantially circular base, the excavating 20 of a radial extension, the driving of a stake near the end of said extension, the covering of the bottom of the base with soft concrete, the insertion of a post in the base excavation, and the filling around the post and in the 25 extension with soft concrete embedding the post and head of the stake.
12. The process of forming a concrete post foundation comprising the excavating of a substantially circular base, the excavating 30 of a radial extension, the driving of a stake near the end of said extension, the covering of the bottom of the base with soft concrete, the insertion of a post in the base excavation, and the filling around the post and in the 35 extension to a height adjacent to the head of the stake, the placing of a reinforcing member with its ends adjacent to the post and stake upon the surface of the concrete and
- the filling of the remainder of the excavation to embed the end of the post, the reinforcing 40 member and the head of the stake.
13. The process of forming a concrete post foundation comprising the excavating of a substantially circular base, the excavating of a plurality of radial extensions, the driving 45 of a stake near the end of each extension and the filling of the excavation with soft concrete embedding the heads of the stakes therein.
14. The process of forming a concrete post foundation comprising the excavating of a 50 substantially circular base, the excavating of a plurality of radial extensions, the driving of a stake near the end of each of said extensions, the covering of the bottom of the base with soft concrete, the insertion of a 55 post in said excavation, and the filling of the excavation around the post and in the extensions with soft concrete embedding the end of the post and heads of the stakes.
15. The process of forming a concrete post 60 foundation comprising the excavating of a substantially circular base, the excavating of one or more radial extensions, the excavating of a depression near the end of each extension, the driving of a stake through 65 each of said depressions, the covering of the bottom of the base with soft concrete, the insertion of a post in said excavation and the filling of the excavation around the post and in each extension with soft concrete embed- 70 ding the end of the post and heads of the stakes.
